[57] **CLAIM**

The ornamental design for a sample cup holder or similar article, as shown and described.

DESCRIPTION

FIG. 1 is a perspective view of sample cup holder or similar article showing our new design;

FIG. 2 is a fragmentary exploded view thereof, the sample cup being shown in broken lines for illustrative purposes only and forming no part of the claimed design;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and,

FIG. 8 is a bottom plan view thereof.

FIG. 1

FIG. 2
